UNITED STATES PATENT OFFICE.

FREDERICK ULRICH, OF PERU, INDIANA.

WAGON-AXLE.

SPECIFICATION forming part of Letters Patent No. 278,755, dated June 5, 1883.

Application filed March 19, 1883. (No model.)

To all whom it may concern:

Be it known that I, FREDERICK ULRICH, a citizen of the United States, residing at the city of Peru, in the county of Miami and State of Indiana, have invented certain new and useful Improvements in Trussed Axle-Supports for Wagons and Vehicles; and I do hereby declare that the following is a full, clear, and exact description of the same, reference being had to the annexed drawings, making a part of this specification, and to the letters and figures of reference marked thereon.

Figure 1 of the drawings is a front elevation of an axle and attachments with my invention applied; Fig. 2, an under plan view of a portion thereof; Fig. 3, a sectional view of a portion of a thimble-skein embodying my invention; Fig. 4, a modification of the same, and Fig. 5 a modification of the truss-connection.

This invention relates to certain new and useful improvements in that class of inventions known as "trussed axles," the object thereof being to provide such a device simple and inexpensive in its construction to overcome the defects heretofore experienced, and thereby effectually strengthen and prevent the axles from sagging or breaking when the wagon or other vehicle upon which they are used is heavily loaded, and also to tighten and hold the skeins securely in place. The objects I attain by the construction substantially as shown in the accompanying drawings and hereinafter more fully described and claimed.

In the drawings, A represents the ordinary wooden axle, provided with thimble-skeins B, said thimble-skeins having the under side of their shoulder portion flattened and a suitable lug or projection, a, depending from their centers, other lugs or projections, b, similar in length and height to the one a, depending from the sides, as shown in Fig. 2. Extending along the under side of the axle A from skein to skein is the truss C, formed preferably of a link shape, with its ends looped around the lug or projection a of each skein, and secured by plates c, having their bearings upon the lugs or projections a b, and held in this position by nuts d upon the screw-threaded ends of suitable clips, e, passing through the plates, said clips passing around the shoulder portion of the skeins. The truss, being virtually slotted from end to end, admits the bolts f, which pass through the

bolster D and hounds E and axle A, suitable washers, g, being interposed between the truss and axle, to increase the tension of said truss upon the thimble-skeins when found necessary, and the whole securely held by suitable nuts working on the screw-threaded ends of the bolts f.

Though I have described the above form of thimble-skein and truss-connection as being preferable, the same may be modified as shown in Fig. 4, in which the truss consists of two separate pieces secured in place between the lugs or projections a b by a suitable bolt passing through said truss and the lugs or projections, the lugs or projections b in this instance being placed in relation to the central one, a, at a distance therefrom not greater than the thickness of the pieces composing the truss, the plates c and clips e being entirely omitted, and, if desired, the lugs or projections b may be also omitted. The truss may also be modified as shown in Fig. 5, which consists of a link or loop having connected to its ends plates or links, which in turn connect with a clevis attachment adapted to be secured to the lugs or projections upon the thimble-skeins, as shown in the modification Fig. 4.

It will be seen from the foregoing that the truss is secured directly to the thimble-skeins, and requires no particular mechanical skill to perform the operation, thus admitting of the tension being regulated at any time by interposing washers of suitable thickness between the truss and axle without the necessity of taking the vehicle to the shop or calling upon the services of a skilled workman; and the truss being directly connected to the skeins, said skeins are at all times kept up snugly in place, thereby preventing the sagging or breaking of the axles; and the skeins being thus kept up in their proper position, the wheels revolving thereon cannot be thrown out of position when the wagon or vehicle is heavily loaded, this being usually the case, resulting from the sagging or bending of the axles under strain, thereby increasing the liability of the said axles to break off close to their skeins.

Having now fully described my invention, what I claim as new, and desire to secure by Letters Patent, is—

1. The thimble-skeins B, formed with lugs a, in combination with the truss C, consisting

of two bars, either separate or connected together in the form of a link, said truss embracing the sides of the lugs, and held thereon by means substantially as shown, and for the 5 purpose set forth.

2. The thimble-skeins B, having lugs *a b*, in combination with the link-shaped truss C and plates *c*, with the nuts and clips for holding the plate in position, substantially as and for 10 the purpose specified.

3. The thimble-skeins B, having upon their under side lug or lugs, in combination with

the truss C, constructed as described, and the washers *g*, interposed between the truss and axle and removable therefrom, whereby the 15 tension of the truss may be increased, substantially as and for the purpose set forth.

In testimony that I claim the above I have hereunto subscribed my name in the presence of two witnesses.

FREDERICK ULRICH.
